GARMENT HOLDER

Morris Cohen, Kearney, N. J.

Application November 22, 1935, Serial No. 51,059

6 Claims. (Cl. 223—71)

This invention relates to garment holding devices, such as shirt envelopes.

One object of the invention is to provide a device of the character described having improved means for holding a collar; improved means for supporting the shoulder portions; improved means for holding the body of a garment against longitudinal and lateral movements; improved means for holding a garment in display position; an improved association of elements for releasably locking a garment in position and for facilitating the engagement of the garment in the said position.

Another object is to provide a device adapted to be cheaply constructed by an improved method adapted for quantity production.

Another object is to provide an improved device having few and simple parts, and which is durable, reliable and efficient in use.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a plan view of a device embodying the invention, with a garment applied thereto.

Fig. 2 is a plan view of the device open as in Fig. 1, without the garment.

Fig. 3 is a longitudinal sectional view taken on the line 3—3 of Fig. 2, of the device open as in Fig. 1.

Fig. 4 is a transverse sectional view on the line 4—4 of Fig. 2.

Fig. 5 is a plan view of the blank element of the device prior to the assembling thereof.

Fig. 6 is an enlarged fragmentary view of a garment holder portion, with parts of the collar in section and other parts thereof in dot-dash lines.

Fig. 7 is a fragmentary plan view of a modification of the invention.

The advantages of the invention as here outlined are best realized when all of its features and instrumentalities are combined in one and the same structure, but, useful devices may be produced embodying less than the whole.

It will be obvious to those skilled in the art to which the invention appertains, that the same

may be incorporated in several different constructions. The accompanying drawing, therefore, is submitted merely as showing the preferred exemplification of the invention.

Referring in detail to the drawing, 10 denotes 5 a device embodying the invention and adapted to hold a suit, coat or shirt 11 having the usual collar 12.

The device 10 may include means for holding a garment, including means for releasably locking the collar or adjacent garment portion against movement in any direction, by engagement with the collar or portion as a whole rather than with a particular point or section of the collar or garment. Of course the collar or garment 10 portion holding means may or may not be used with a means for holding the body of the garment. Also, a garment collar may be considered similar or equivalent to adjacent portions of the garment, with particular reference to the shoulder portions of the garment. But the invention may be viewed as involving novel shoulder holding portions in improved relation with a collar holding portion or a portion for holding the garment body, or both.

The garment holding means may include a support, back, or interconnecting element 13 of suitable size and shape, for instance, rectangular, and being substantially coextensive with the garment as in a conventional longitudinally and transversely folded position thereof.

At a point such as the lower end of the element 13 I may provide a holding means or band 14 adapted to receive the garment. This band may be omitted.

At a point spaced along the element 13 from the band 14, I provide a locking means for the garment which may be embodied in a unitary means such as a band 15. This band may have a pair of spaced slits 16 tapering upwardly toward each other, and being interconnected by a slit 17 having a downward notching slit portion 18 intermediate of the slits 16. Thus a downward projecting tongue 19 is provided, which may be of upward supporting or wedging character, and which can be of any desired width and length. Likewise a collar supporting band portion 20 is provided having a downward extending notch 18 so that the part 20 is adapted to externally engage the collar under the wings thereof, with the notch 50 receiving and supporting the collar at the front adjacent to the fold line of the collar to thus assure support for the wings of the collar.

The slits 16 may terminate at their upper ends in short slits 21 that extend toward each other to 55

facilitate movement of the tongue 19 relative to the plane of the band 15, and to facilitate longitudinal convexing of the tongue to permit its ready insertion into the shirt.

5 In practice, the folded garment is inserted through the bands 14, 15 downward, and when in proper position therein, the tongue 15 is sprung into the shirt through the collar thereof. Then the element 20 is sprung under the collar wings 10 and the assembly according to Fig. 1 is completed.

As shown in Fig. 6, the side edges 22 of the tongue 19, defined by the slits 16, bear snugly against opposite sides of the collar internally thereof to tautly maintain the latter flat. Also 15 the said edges may bear against and support the shoulder portions 23 of the garment.

As a display, the device 10 permits the garment to be readily viewed as to quality, laundering, etc. Further the display is neat and novel, the tongue 20 19 concealing the back of the garment at the collar, with the point 24, resulting from the notch at 18, readily fitting the contour of the collar as shown in Fig. 6. The assembly may be freely manipulated as a display, and yet, with the garment 25 reliably held.

It is seen that lateral movement of the garment is prevented by the bands 14, 15, downward movement is prevented by the shoulder engaging tongue 19 and the collar support 20; and upward 30 movement is prevented by the arrangement of the tongue 19 extending into the garment and being connected at its neck 25 to the band 15. Also any tendency for downward movement of the garment results in a transverse stretch of the 35 collar by the wedge tongue 19, and thus relieves the pressure of the collar against the element 20, whereby possible distortion of the collar is avoided.

A particular advantage of the device 10 is the 40 saving of material in an "envelope" holder. Approximately 40% of the material is saved, and a superior and attractive result produced. The cost of material is a primary item in a device of this type.

45 The modification shown in Fig. 7 shows a band 15a generally similar to that at 15, except that the slits 21a may be longer than those at 21 and may be interconnected by a fold line 26; further a simple straight slit 17a may be used in place of the 50 slit 17, and if desired, the element 20a may be engaged over the wings of the collar to hold them down, instead of being positioned thereunder as in Fig. 1. If desired, the cross fold portions of the collar at 27 may overlie adjacent portions of 55 the band 15a instead of underlying the same as in the device 10 to thus improve the interlock for the collar. The garment will be held in all directions, and certain features of this modification may be used in the device 10.

60 The method of making the devices will now be briefly described. In Fig. 5 are shown blanks 28, 29, 30 corresponding to the elements 15, 13 and 14 respectively. The blanks 28 and 30 may have score lines 31, 32 respectively, to provide 65 flanges 33, 34 foldable above the edges of the blank 29 and adapted to be secured to the back surface of the blank 29 as by adhesive. The slits 16, 17, 18 and 21 are preformed in the blank 28, and there is no waste material at all. If desired, 70 the blanks 28, 30 may be cut from a single sheet of paper or other stiff or pliable material.

I claim:

1. A device for supporting a collar including a member having a relatively long slit, transverse closed ended relatively short comparatively

straight slits extending convergently from the ends of the long slit, on one side of the latter, the long slit having a notch forming slit portion on the opposite side thereof centrally related to the short slits, the portion of the member defined by said slits constituting a tongue connected to the member and adapted to be downwardly inserted into a closed collar for longitudinally stretching the same to keep the collar flat, the connection of the tongue and the member being in proximity to the ends of the relatively straight converging slits, with a portion of the collar supported in said notch, and the member having parts defined by said short slits for affording additional supporting engagement for the collar. 15

2. A device for supporting a collar including a member having a relatively long slit, transverse closed ended relatively short comparatively straight slits extending convergently from the ends of the long slit, on one side of the latter, said slits defining a tongue having sufficient width for relatively snug dovetail downward engagement in a collar, within the neckband thereof, the short slits terminating in slits that extend directly toward each other up to the connection of the tongue and the member, the short slits receiving and confining the sides of the collar, and garment supporting means, said member being connected to an end of said means so that the direction of convergence of the short slits is toward said end, the said tongue lying flatwise substantially along the plane of said member in collar holding position. 20

3. A device including a first member for supporting a garment, a second member for holding a collar connected to an end portion of the first member, the second member having a relatively long slit transverse to the first member, relatively short slits extending from the ends of the long slit toward the adjacent end of the first member 35 to provide a tongue projecting toward the remote end of the first member, said tongue lying flatwise along the plane of the first member and being sufficiently wide to be adapted to project into a collar to hold the same in flat expanded position 40 against said first member, and the size of opening afforded by the tongue and slits being sufficient to permit the collar ends to be passed outward through said opening to overlie the lower edge of the long slit. 45

4. In combination, a garment having a collar and a member for holding said collar, said member having a longitudinal slit and transverse end slits leading therefrom to provide a tongue and define an opening upon moving the tongue from the plane of the member, said tongue projecting downward into the collar, and the latter having the wing ends thereof passed through said opening to overlie the member at the lower edge of 50 said opening. 55

5. In combination, a collar, and a member for holding the collar flat and for limiting lateral and vertical movement thereof relative to the member, said member having a slit forming a tongue connected at one end to the member, said tongue 65 providing an opening in the member on deflecting the tongue from the plane of the member, said tongue having its side edges converging toward its connecting end with the member, said tongue having downward dovetail engagement with the 70 collar interiorly thereof to expand the collar flatwise and prevent release of the collar from the tongue, with the side edges of the opening additionally limiting relative lateral movement of the collar and the closed ends of the slit preventing 75

relative upward disengaging movement of the collar.

6. In combination, a garment having a collar and shoulder portions, and a support including a member lying at one side of the garment parallel thereto, said member having slits providing a downward extending tongue having downward di-

verging side edges, said tongue lying substantially in the plane of the member and being snugly fitted in said collar and having its diverging edges extended to support the shoulder portions of the garment.

5

MORRIS COHEN.
